UNITED STATES PATENT OFFICE.

WILLIAM CRAWFORD, OF BRADFORD, PENNSYLVANIA, ASSIGNOR TO
BOVAIRD & COMPANY, A COPARTNERSHIP.

GEARING.

No. 846,285.

Specification of Letters Patent.

Patented March 5, 1907.

Application filed February 6, 1906. Serial No. 299,827.

To all whom it may concern:

Be it known that I, WILLIAM CRAWFORD, a citizen of the United States, residing at Bradford, Pennsylvania, have invented certain new and useful Improvements in Gearing, of which the following is a specification.

My invention relates to improvements in pumping and hoisting machinery for use in connection with oil, gas, and water wells, and the object of the invention is to devise a simple, durable, and efficient form of mechanism which may be installed in a much more economical manner than the machinery ordinarily employed and which will require but few changes to adapt it for either pumping or pulling the material out of the well or lowering it back again, such changes as are necessary being quickly and easily made.

With these and other objects in view the invention comprises the construction and arrangement of parts hereinafter described, and particularly set forth in the appended claims.

The invention is illustrated in the accompanying drawings, in which—

Figure 1 is a plan view; Fig. 2, a side elevation. Figs. 3, 4, and 5 are detail views.

Referring more particularly to these drawings, the numeral 5 designates a driving-shaft, to the crank of which is connected the piston 6 of an ordinary reciprocating engine 7, the shaft being journaled in a base 8 of the ordinary or any desired construction. The shaft carries on one end the ordinary fly-wheel 9 and on the opposite end a gear wheel or pinion 10. This pinion 10 is encircled at a suitable distance by an internal stationary rack 11, which may conveniently be carried by a disk or plate 12, which may be supported by and firmly secured to the foundation of the engine or other convenient part by means of braces 13 and forms the back of the gear-case, the stationary plate and the annular rack carried thereby constituting, in effect, a gear-case having an open side, and this open side is closed by a rotary disk or plate 14, journaled upon the projecting end of the shaft. The rotary plate may be held from longitudinal movement on the shaft by any suitable means, such, for instance, as cleats 16, removably secured to lugs 15 on the gear-case and overlapping the edge of the rotary disk. Planet-gears 17, journaled on studs 18, mesh with the pinion 10 on the

driving-shaft and also with the internal stationary rack.

It will thus be seen that as the driving-shaft is rotated by the engine the pinion 10 will rotate the planet-gears 17, and as these planet-gears are in mesh with the stationary rack they will be caused to travel around the driving-shaft at a much reduced speed, carrying with them the rotary plate or disk 14, upon which the are journaled. In order to utilize the rotation of this plate 14 for either operating the pumping mechanism or the hoisting mechanism, I connect to the plate removable and interchangeable parts in the manner hereinafter described. The plate is provided with a stud 19 for receiving the wrist-pin 20 of a pitman 21, connected to a pumping-jack or walking-beam for operating the pump mechanism. The rotary disk has a hub 23, over which is designed to be placed the tubular extension 24 of a drum 25, designed to receive a hoisting-rope. When the apparatus is to be used for hoisting purposes, the pitman and connecting wrist-pin are removed, the drum extension inserted over the hub and secured in place by bolts 26, and thus it will be seen that with these slight changes the apparatus is quickly adapted for lowering the pumping apparatus into the well or hoisting it therefrom.

In order to relieve the strain from the bolts 26, the hub may be provided with an integral key or lug 27, designed to engage a keyway in the tubular extension of the winding-drum.

Having thus described my invention, what I claim is—

1. In combination, a driving-shaft, a stationary plate having an annular gear encircling the shaft and constituting a gear-case with an open side, a disk journaled on the driving-shaft and closing said open side, a pinion on the driving-shaft within the gear-case, a planet-gear journaled on the plate within the gear-case and meshing with both said pinion and rack, said rotary disk having a centrally-arranged projecting hub and an eccentrically-arranged boss arranged respectively for the attachment of a winding-drum and a wrist-pin, substantially as described.

2. In combination, a driving-shaft, a stationary plate through which said shaft projects, said plate having an annular flange carrying internal rack-teeth, said plate and

flange forming a gear-case, a pinion on the driving-shaft within the gear-case, a rotary disk rotatably mounted on the driving-shaft and closing the open side of said case, a
5 planet-gear carried by said disk within the gear-case and meshing with said rack and pinion, removable cleats carried by said annular flange and overlapping the edge of the disk, and means for detachably connecting

the part to be operated to said disk, substantially as described.

In testimony whereof I affix my signature in presence of two witnesses.

WILLIAM CRAWFORD.
